UNITED STATES PATENT OFFICE

FOISTER S. RIMER, OF WASHINGTON, DISTRICT OF COLUMBIA

TOY AEROPLANE

Application filed January 3, 1930. Serial No. 418,319.

This invention relates to toy aeroplanes, and the purpose of the improved construction is to provide for rotation of a substantial part of the body portion of the device, bearing pictures or the like or having variously colored portions adapted to attract a child's attention when rotated; and it consists of the construction and arrangement of parts in general and detail, as more fully herein-
10 after described and claimed.

In the accompanying drawings:

Figure 1 is a side view of a toy aeroplane embodying the invention;

Figure 2 is a longitudinal vertical section 15 of the improved device;

Figure 3 is a section on the line 3-3 of Figure 2;

Figure 4 is a section on the line 4-4 of Figure 5;

20 Figure 5 is a detail view of the spring and gear mechanism for manually rotating the rotatable body portion;

Figure 6 is a side view showing the spring and gear mechanism and its housing de-
25 tached from the device; and

Figure 7 is a fragmentary bottom plan of the rotatable body portion.

Referring more particularly to the drawings wherein similar numerals are utilized 30 to indicate corresponding parts in the several views, the numeral 1 designates the aeroplane generally, the body of which comprises stationary forward and rear substantially cylindrical portions 2 and 3 respectively, and an intermediate rotatable section or portion 4, also of substantially cylindrical shape. A bar 5 secured at its forward end to the section 2 by bolts or the like 6, and at its other end to the section 4 by means of a headed

35 bolt 7 passing through the elongated slot 8, serves to connect these body sections in spaced relation. The intermediate rotatable section 4, is slightly contracted at each end as at 9 and 10 to fit loosely within the respective 40 front and rear body sections 2 and 3 thus maintaining the cylindrical stream line contour throughout the entire length of the body.

A propeller shaft 11 carrying a propeller 12 on its forward end extends axially through 50 the end walls of the respective sections 2, 3

and 4 and is secured in place by nuts 13 threaded on its rear end. Any slight necessary adjustment of the rear body section 3 toward or away from the intermediate body section 4 can be effected by virtue of slot and bolt connection 7-8 between the bar 5 and the rear body section 3. The rotatable intermediate section 4 is secured to the propeller shaft by means of a flanged sleeve 13 keyed to the shaft by key 14, the flange 15 of the sleeve being bolted to the forward end wall of the section 4.

Front wheels 16 are secured to an axle 17 in turn connected to the forward body section 2 by means of brackets 18 bolted to opposite sides of the section 2 as at 19. These brackets 18 which support a plane 20, also serve as a convenient hand hold. A rear wheel 21 loosely mounted on an axle 22 is secured to the rear stationary body section 3 by means of bracket 23, and this section 3 carries the usual rudder 24 and elevators 25. Rotation of the variously colored intermediate body section 4 is effected either by means of the hand operated spring gear mechanism, designated generally by the numeral 26, or by pushing or pulling the device over the floor or other surface. Rotation of the wheels 16 by the latter method is communicated to the propeller shaft 11 by means of a cable or belt 26' passing over drums 27 and 28 fixed to the front wheel axle 17 and loosely mounted upon the propeller shaft respectively, a guide pulley 29 loosely mounted on a fixed shaft 30 being employed to keep the belt from slipping. A clutch 31, keyed for slide-
70 able movement upon the propeller shaft, permits of the running gear being connected or disconnected from the shaft at the will of the operator, and it will of course be understood that when it is desired to rotate the propeller shaft by drawing the device over the floor, the clutch 31, will be moved into engagement with the hub of the drum 28. Any suitable means as shown by chain dotted lines 75 may be provided for manually shifting the clutch into and out of engagement with the drum. When the drum 28 has been fixed to the propeller shaft, by appropriate move-
80 ment of the clutch, rotation of the wheels 16

Front wheels 16 are secured to an axle 17 in turn connected to the forward body section 2 by means of brackets 18 bolted to opposite sides of the section 2 as at 19. These brackets 18 which support a plane 20, also serve as a convenient hand hold. A rear wheel 21 loosely mounted on an axle 22 is secured to the rear stationary body section 3 by means of bracket 23, and this section 3 carries the usual rudder 24 and elevators 25. Rotation of the variously colored intermediate body section 4 is effected either by means of the hand operated spring gear mechanism, designated generally by the numeral 26, or by pushing or pulling the device over the floor or other surface. Rotation of the wheels 16 by the latter method is communicated to the propeller shaft 11 by means of a cable or belt 26' passing over drums 27 and 28 fixed to the front wheel axle 17 and loosely mounted upon the propeller shaft respectively, a guide pulley 29 loosely mounted on a fixed shaft 30 being employed to keep the belt from slipping. A clutch 31, keyed for slide-
70 able movement upon the propeller shaft, permits of the running gear being connected or disconnected from the shaft at the will of the operator, and it will of course be understood that when it is desired to rotate the propeller shaft by drawing the device over the floor, the clutch 31, will be moved into engagement with the hub of the drum 28. Any suitable means as shown by chain dotted lines 75 may be provided for manually shifting the clutch into and out of engagement with the drum. When the drum 28 has been fixed to the propeller shaft, by appropriate move-
80 ment of the clutch, rotation of the wheels 16

causes the body section 4 to rotate, much to the interest of the operator whose attention will immediately be attracted by the action thus set up, also by the changing colors.

5 The spring gear mechanism 26, previously referred to is mounted in a housing 32 positioned within and fixed to the forward body section 2. It consists of a large gear 33 and a pinion gear 34, fixed to a short shaft 35, the ends of which extend loosely into substantially vertical short slots 36, formed in the opposing vertical walls of the housing. The short shaft 35 normally seats by gravity in the bottom of slots 36 thus maintaining gear 15 33 normally out of engagement with a small pinion gear 37, mounted on the flanged sleeve 13, previously referred to. A trigger 38, secured intermediate its ends upon a short shaft 39, mounted for rotation in the housing 20 32, is formed with a finger grip 40 and a toothed segmental portion 41, the latter engaging the pinion 34. Operation of the propeller shaft by means of the mechanism is effected as follows:

25 The operator holds the device in one hand by grasping the plane 20 or one of the brackets 18, and after placing the thumb of the other hand against the depending extension 42 formed on the forward body portion for 30 this purpose, presses the trigger inwardly to the dotted line position illustrated in Figure 4. This causes the toothed portion 41 to ride up over and rotate the pinion 34 and to also elevate the shaft 35 in slots 36, thus moving 35 gear 33 into mesh with pinion 37. It will thus be seen that actuation of the trigger in the manner described causes rotation of the propeller shaft. When finger pressure on the trigger is released, the shaft 35 will drop 40 by gravity to the bottom of slots 36, and the trigger will be returned to its original set or full line position by means of spring 43. A stop 44 on the trigger engages the housing and limits the extent of this return movement. It is desirable that the running gear 45 be disconnected from the propeller shaft prior to actuation of the trigger but this is not necessary.

It will be understood that by making slight 50 changes, in the forward body section 2, that the device could be mounted on the radiator cap of an automobile. When so mounted the propeller 12 will have sufficient propelling force to rotate the body section 4.

55 Having thus described my invention what I claim as my invention is:

1. A toy aeroplane having a symmetrically shaped body comprising front and rear sections and an intermediate section, a propeller 60 shaft fixed to and mounted for rotation with said intermediate section, means for maintaining the ends of said intermediate section in spaced relation to the opposing ends of the said front and rear sections, and means for 65 rotating the propeller shaft.

2. A toy aeroplane having a body comprising a plurality of fixed and movable sections arranged end to end, a propeller shaft mounted for rotation in certain of said fixed sections, and one of said movable sections being connected to said shaft for rotation therewith, means for maintaining the opposing ends of said fixed and movable sections in spaced relation to each other, and means for 70 rotating said propeller shaft.

75 In testimony whereof I affix my signature.
FOISTER S. RIMER.
